UNITED STATES PATENT OFFICE.

ROBERT A. SMITH, OF PHILADELPHIA, PENNSYLVANIA.

HAIR-CUTTING DEVICE.

Application filed August 23, 1920. Serial No. 405,356.

To all whom it may concern:

Be it known that I, ROBERT A. SMITH, a citizen of the United States, residing at Philadelphia, in the county of Philadelphia and State of Pennsylvania, have invented certain new and useful Improvements in Hair-Cutting Devices, of which the following is a specification.

One object is to provide a device of a simple and durable construction which will enable a person to easily, quickly and evenly cut the hair of another person or to cut their own hair.

Another object is to so construct my improved hair cutting device that it can be used with equal facility in either the right or left hand and can be readily adjusted to suit various requirements.

These objects, and other advantageous ends which will be described hereinafter, I attain in the following manner, reference being had to the accompanying drawings in which—

Figure 1 is a face view of a hair cutting device made in accordance with my invention,

Figure 2 is a fragmentary view of the same general character as shown in Figure 1 illustrating a change in position of certain of the parts of my improved device,

Figure 3 is an enlarged section taken on the line 3—3 of Figure 1, and

Figure 4 is a fragmentary view showing another position of the handle spring contracted and held in the contracted position by a link to keep the cutting blades of the device closed.

Referring to the drawings, 5 represents a pair of shears which include cutting blades 6 and 7 which are pivotally connected together at 8 and which have handle portions respectively indicated at 9 and 10. Each of the handle portions has one end of a looped spring 11 secured thereto upon its inner surface; the opposite ends of said looped springs being bowed inwardly and joined together by any suitable means such as shown at 12 so that by moving the handle portions 9 and 10 together against the action of the springs 11 the blades will be moved together and the looped springs will be compressed. Upon release of the compressing action the looped springs will expand into their normal positions and thereby again open the blades 6 and 7.

The blade 7 has a tongue 13 extending lat-

erally therefrom and substantially in the same plane as the cutting edge of the blade 7 and said tongue 13 is adapted to be slid through slots 14 in a hollow housing 15; 60 said housing having a binding or set screw 16 screwed therein and adapted to engage the tongue 13 and hold the latter in connection with the housing as clearly shown in Figure 3. The housing 15 is connected to 65 one end of a looped spring 17; said looped spring being substantially U-shape as clearly shown in Figure 3. The opposite end 18 of said spring 17 is secured to an extension 19 of a comb 20; said comb being positioned 70 substantially parallel with the plane of cutting movements of the blades 6 and 7 and is so disposed, as clearly shown in Figures 1 and 2, that the cutting edge of the blade 7 is directly over or under the teeth 21 of the comb according to the position of the comb, since it will be noted that the comb may be removed and inverted so as to occupy either the position shown in Figure 1 75 or the position shown in Figure 2; it merely 80 being necessary to loosen the screw 16 and withdraw the tongue 13, after which the comb can be inverted so as to occupy a position at the opposite face of the blade 7 and again connected with the tongue 13 secured to the housing. 85

The comb 20 can be moved toward or from the blade 7 by the following means: A screw threaded post 22 projects from the extension 19 through a slot 23 in an extension 24 of the housing 15; said extension 24 forming the means of connection between the spring 17 and the housing 15. A nut 25 is positioned on the screw threaded post 22 and bears against the outer face of the extension 24. A lock nut 26 is preferably provided on the post 22 and adapted to engage the inner surface of the extension 24 as clearly shown in Figure 3. Thus by turning downwardly upon the nut 25, the spring 17 will be compressed and the comb and blade 7 will be moved toward each other so as to vary the distance between the comb and blade for a purpose hereinafter described. 100

In the use of the device for cutting hair, 105 the comb can be drawn through the hair against the scalp of a person's head and the distance between the comb and the blade 7 as shown in Figure 1 will determine the length of the hair to be cut; it being noted that as the comb is drawn through the hair, 110 the shears are operated so as to cut the hair

projecting through the teeth of the comb. If it is desired to change the position of the comb such for example as changing from the right to the left hand, the comb can be removed as above described and changed to the position shown in Figure 2.

When the device is not desired for use, I preferably compress the handle sections and apply an open link 27 in a position embracing the upper portion of the looped springs 11; the ends 28 of the handles serving as abutting means to prevent the link 27 from moving upwardly and the springs 11 compressing sufficiently to form bowed portions 11^a so as to hold the link in position.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A hair cutting device including cutting blades, a comb, a flexible loop carrying the comb, and means on one of said blades affording attachment of the loop thereto.

2. A hair cutting device including cutting blades, a comb, a loop carrying the comb, and means on one of said blades affording attachment of the loop thereto.

3. A hair cutting device including a pair of shears having blades movably connected together; a comb; a flexible connection for said comb to the shears; and means for varying the tension of said flexible connection whereby the comb can be moved toward or from the cutting plane of the blades; substantially as described.

4. A hair cutting device including two co-operating cutting blades, one of said blades

having a projecting tongue; a housing having a slot therein through which said tongue can be projected; a binding screw in said housing adapted to clamp said tongue thereto; and a comb positioned adjacent the cutting edge of said blades and connected to said housing; substantially as described.

5. A hair cutting device including two co-operating cutting blades, one of said blades having a projecting tongue; a housing having a slot therein through which said tongue can be projected; a binding screw in said housing adapted to clamp said tongue thereto; a comb; a looped spring having its opposite ends respectively secured to said comb and housing; and means for compressing said spring whereby the comb is moved toward said cutting blades; substantially as described.

6. A hair cutting device including two co-operating cutting blades; a comb located adjacent the cutting edges of said blades; a looped spring having its end portions respectively secured to one of said blades and to said comb; and means for compressing said spring whereby the comb will be moved toward said cutting edges; substantially as described.

7. A hair cutting device including two co-operating cutting blades; a comb located adjacent the cutting edges of said blades; a looped spring having its end portions respectively secured to one of said blades and to said comb; and co-acting screw threaded members for compressing said spring whereby the comb is moved toward the cutting edges of said blades; substantially as described.

In testimony whereof I have signed my name to this specification in the presence of two subscribing witnesses.

ROBERT A. SMITH.
